GRAIN REGULATOR

Chester D. Strehlow, Spokane, Wash.

Application December 11, 1948, Serial No. 64,880

5 Claims. (Cl. 222—55)

1

This invention relates to a grain regulator and it is one object of the invention to provide a regulator which will control flow of grain from a bin or other storage receptacle and very effectively restrict the flow of grain to a predetermined amount in a given time.

Another object of the invention is to provide a grain regulator a body or casing through which the grain flows from a chamber at the top of the housing to an outlet at the bottom thereof, a gate being mounted in the housing in such relation to the outlet of the upper chamber that flow of grain from the chamber will be controlled, means being provided externally of the housing for adjusting the position of the gate relative to the outlet of the chamber.

Another object of the invention is to provide a grain regulator wherein the gate is mounted at the inner end of an arm which projects outwardly from the housing and is pivoted to a supporting arm which in its turn is pivotally mounted and carries a weight which is adapted to be shifted longitudinally of the supporting arm and serves to hold the gate in an adjusted position.

Another object of the invention is to provide within the housing a deflector plate which is pivotally mounted in position for engagement by grain flowing downwardly from the upper chamber of the housing and serves to move the gate towards a closed position if too much grain is flowing from the chamber.

Another object of the invention is to so mount the deflector plate that when the weight is shifted along the supporting arm the deflector will be at the same time tilted to adjusted positions and thus caused to accommodate itself to different kinds of grain.

Another object of the invention is to provide a regulator of such construction that it may be easily mounted over a storage bin and indicate the amount of grain flowing from a receiving bin or the line to the storage bin.

The invention is illustrated in the accompanying drawings wherein:

Fig. 1 is a perspective view of the improved grain regulator.

Fig. 2 is a sectional view taken vertically through the grain regulator.

Fig. 3 is a fragmentary sectional view taken along the line 3—3 of Figure 2.

Fig. 4 is a fragmentary sectional view taken along the line 4—4 of Figure 2.

This improved grain regulator has a housing 1 which is open at its top and bottom and has its lower end surrounded by an attaching flange 55

2

2 and its upper end surrounded by a flange 3. The front wall 4 of the housing has an upper portion 5 extending at a rearward incline so that the inlet 6 at the top of the housing is considerably smaller than the outlet 7 at the bottom of the housing and thus allow grain flowing downwardly through the housing to freely flow out of the open bottom of the housing. A sight opening 8 is formed through the lower portion of the rear wall 9 of the housing so that an attendant may observe flow of grain through the housing; this sight opening being normally closed by a plate or door 10. The door or closure plate is mounted upon a pivot pin 11 projecting from the rear wall above the sight opening and at its lower end the door carries a knob 12 by means of which it can be easily swung to an opened position. A spring 13 about the pin 11 urges the door towards the housing and this spring is held upon the pin by a nut 14 which is sufficiently tightened to place the spring under tension and cause it to hold the door in frictional binding engagement with the rear wall of the housing. Near its upper end the rearwardly extending portion 5 of the front wall is formed with a transversely extending opening 15 and from this opening leads a slot 16 which extends downwardly through the front wall to a point near the lower end thereof, as shown in Figure 2. Plates 17 and 18 are mounted in the upper portion of the housing, and from an inspection of Figure 2 it will be seen that the plate 17 extends forwardly at a downward incline from the rear wall of the housing and that the plate 18 extends downwardly from the front wall above the opening 15. These plates form a bottom and a front wall for a chamber 19 in the upper end of the housing and since the front plate has its lower edge spaced upwardly from the lower plate 17 there is provided an outlet 20 through which grain may flow from the chamber and downwardly through the housing towards the open lower end of the housing through which it will freely flow as the outlet 7 at the bottom of the housing is a great deal larger than the entrance opening 6 and the outlet 20.

Brackets 21 extend forwardly from the front wall of the housing in spaced relation to opposite sides of the slot 16 and taper towards their front ends where they are formed with bosses 22 through which pass end portions of a shaft 23 having threaded end portions upon which nuts 24 are screwed to hold the shaft against turning and longitudinal movement out of the bosses. An arm 25 formed of companion bars 25'

mounted in side by side relation to each other extends through the slot 16 and at its inner end carries a gate 26 which serves as a closure for the space or outlet 20 between the plates 17 and 18, and referring to Figure 2 it will be seen that the gate is arcuate vertically and rests upon the lower or free end of the plate 17 when in the closed position. Outer portions of the bars 25' form a fork 27 carrying sleeves 28 through which pass portions of the shaft 23. This shaft passes transversely through an airtight casing 29 and the intermediate portion of the shaft 23 engages in the bearing recess or arcuate groove 30 formed in the wall 31 of the casing and its end portions passing through bearings 32 which are mounted in bosses 33 projecting from opposite sides of the casing, the bearings 32 being held in the pockets 34 formed in the bosses by the sleeves 28 which pivotally surround the bosses. The casing 29, which has an arcuate wall 35, is mounted substantially midway the length of a balancing bar 36 and within the casing is a vane or fin 37 which is secured to shaft 23. Since the casing 29 is airtight and the edges of the fin have close fitting engagement with the walls of the casing 29, the bar 36 and arm 25 will have a smooth tilting movement and not a fast rocking movement, the fin acting as a suppressor. Therefore the gate will gradually move towards an opened or closed position and will remain in its adjusted position during the flow of grain through the housing 1. The bar 36 is open along its under face, as shown in Figures 2 and 3, and within the channel of the bar are mounted bearing plates 38 and 39 which serve to rotatably mount a threaded rod 40 carrying a weight 41 which has at its upper end a neck 42 formed with a threaded opening to receive the threaded shaft. The reduced end portion 43 of the shaft 40 which has its outer end rotatably mounted in a bearing 44 is threaded in an opposite direction to the threads of the shaft 40 and carries a cross bar 45 which moves in a direction opposite to that of the weight when the shaft 40 is turned through the medium of its operating knob 46. This knob is mounted upon the outer end of the shaft 40 and has scale markings 47 about the circumference of its inner end portion and at the outer end of the balancing bar 36 is a pointer 48 so that a person may accurately determine the extent to which the shaft 40 has been turned when adjusting the grain regulator. Ends of the cross bar 45 engage under shoulders 49 formed along inner faces of the side walls 36' of the balancing bar 36 to prevent the cross bar from turning with the reduced end portion 43 of shaft 40, thereby causing the cross bar to move along the threaded shaft and longitudinally of the balance bar when the shaft is rotated. The under portion of the cross bar is formed with notches or recesses 50 into which fit arms 51 which pass through the lower portion of the opening or slot 16 and have their inner ends pivoted to a deflector plate 52 disposed within the housing 1 and pivoted at its upper end to the inner end of the balancing bar by a pin 53. The weight of the deflector plate holds the arms 51 in the recesses 50 so that when the cross bar is moved forwardly along the reduced end portion 43 of the shaft 40 the deflector plate will be tilted downwardly. When the cross bar is shifted rearwardly the arms 51 are forced downwardly and the deflector plate will then be tilted upwardly. When the shaft is rotated to shift the weight and the cross bar towards or away from each other the balancing bar 36 will

be tilted vertically and since this balancing bar has one side wall provided with scale markings 54 and the weight 41 has an arrow or pointer 55 on one side face to cooperate with the scale markings an attendant can readily determine whether the balancing bar is in its proper position. When the cross bar is in the position shown in Figure 2 the gate 26 is closed and is held in this closed position by cam plates 56 which are secured against opposite side faces of the arm or bar 25 by bolts 57 and extend downwardly therefrom with the arcuate lower edges bearing against the cross bar 45. When the cross bar is moved forwardly the weight of the bar 25 raises the gate towards an opened position and since the cross bar moves along the upper edges of the arms 51 the deflector plate 52 will be swung downwardly to an adjusted position.

During use of the grain regulator a quantity of grain is fed into the housing through its upper end and this grain moves downwardly until it strikes the plate or bottom 17 of the chamber 19. The grain then flows along its bottom plate and since the mechanism will be adjusted to hold the gate 26 open the grain will flow through the outlet 20 and drop from the plate 17 towards the bottom of the housing. During this dropping movement the grain will strike the deflector plate and as it flows along this plate it will have a tendency to swing the plate downwardly and hold the arms in close contacting engagement with the cross bar 45 as well as tending to tilt the balancing bar about the pivot shaft 23. By turning the knob the weight and the cross bar may be shifted longitudinally of the balancing bar and when proper adjustment has been made the gate will be held open the desired amount. By applying selected ones of a number of cam plates 51 to the arm 25 the machine may be caused to accommodate itself to the kind of grain which is being delivered into the housing, it being understood that grains of different sizes and weights, such as wheat, oats, corn, and the like, apply more or less depressing force upon the plate 52 when they strike this plate and move downwardly along it.

Having thus described the invention, what is claimed is:

1. A grain regulator comprising a housing having an inlet at its top and an outlet at its bottom, said housing also having an opening at its front, deflectors in the upper portion of said housing forming a chamber open at its top and having a discharge opening at its front, brackets projecting forwardly from the front of the housing at opposite sides of the front opening, a shaft extending between and secured to said brackets, an arm extending through the front opening and having forks at its outer end pivoted about said shaft, a gate at the inner end of said arm movable upwardly from a position in which it closes the discharge opening of the chamber to an opened position by tilting movement of the arm, a balancing bar passing through the front opening and carrying an upwardly extending casing pivoted to the shaft, a fin in said casing carried by said shaft and checking tilting movement of the bar, a rod rotatably mounted longitudinally of the balancing bar and threaded in opposite directions from its front and rear ends, a weight threaded upon and suspended from the forward portion of the threaded rod, a cross bar threaded upon the rear portion of the threaded rod and moved in a direction opposite to that of the weight when the threaded rod is rotated, cam plates mounted at opposite sides of said arm and

extending downwardly therefrom and formed with arcuate edges bearing against the cross bar, a deflector plate within said housing disposed below the bottom of said chamber and pivoted at its upper end to the balancing bar for vertical tilting movement, and arms extending forwardly from the last mentioned deflector plate and outwardly through the opening at the front of the housing with their outer ends extending under the cross bar with their upper edges bearing against the outer face of the cross bar.

2. A grain regulator comprising a housing open at its top and bottom and having a front wall formed with an opening, a chamber in the upper portion of said housing formed with a discharge opening at its front, brackets projecting forwardly from said housing at opposite sides of the front opening, a shaft secured to and extending through the front opening and having its outer end pivotally mounted on said shaft, a gate at the inner end of the arm movable vertically into and out of closing relation to the discharge opening of said chamber by vertical tilting of the arm, a balancing bar pivotally mounted upon the shaft and extending into the housing under the arm, a deflector plate pivoted to the inner end of the balancing bar and extending downwardly therefrom below and forwardly of the discharge opening of the chamber, a threaded shaft rotatably mounted longitudinally of the balancing bar, a weight and a cross bar carried by said threaded shaft and moved longitudinally of the balancing bar in opposite directions when the shaft is rotated, arms extending forwardly from the deflector plate and having upper edges of their forward portions engaged across the under portion of the cross bar, and cam plates carried by and extending downwardly from the first mentioned arm with lower edges bearing against the cross bar.

3. A grain regulator comprising a housing open at its top and bottom and having a front wall formed with an opening, a chamber in the upper portion of said housing formed with a discharge opening at its front, brackets projecting forwardly from said housing at opposite sides of the front opening, a shaft secured to and extending between said brackets, an arm extending through the front opening and having its outer end pivotally mounted on said shaft, a gate at the inner end of the arm movable vertically into and out of closing relation to the discharge opening of said chamber by vertical tilting of the arm, a balancing bar pivotally mounted upon the shaft and extending into the housing under the arm, a deflector plate pivoted to the inner end of the balancing bar and extending downwardly therefrom below and forwardly of the discharge opening of the chamber, a weight shiftable along the balancing bar to adjusted positions, a cross bar back of said weight shiftable along the balancing bar to adjusted positions, a cam carried by the arm and engaging the cross bar, and arms extending forwardly from said deflector plate and out of the housing with its outer portion

engaged across the under portion of the cross bar.

4. A grain regulator comprising a housing open at its top and bottom and having a front wall formed with an opening, a chamber in the upper portion of said housing formed with a discharge opening at its front, brackets projecting forwardly from said housing at opposite sides of the front opening, a shaft secured to and extending between said brackets, an arm extending through the front opening and having its outer end pivotally mounted on said shaft, a gate at the inner end of the arm movable vertically into and out of closing relation to the discharge opening of said chamber by vertical tilting of the arm, a balancing bar pivotally mounted upon the shaft and extending into the housing under the arm, a deflector plate pivoted to the inner end of the balancing bar and extending downwardly therefrom below and forwardly of the discharge opening chamber, a weight under the balancing bar outwardly from the housing, a cross bar back of said weight, means mounting the weight and the cross bar for simultaneous movement along the balancing bar in opposite directions, a cam carried by the arm and engaging the cross bar, and a second arm extending forwardly from said deflector plate and out of the housing with its outer portion engaging the cross bar.
5. A grain regulator comprising a housing open at its top and bottom and having a front wall formed with an opening, a chamber in the upper portion of said housing formed with a discharge opening at its front, a closure for the discharge opening, an arm carrying said closure and pivotally mounted with a portion projecting forwardly from the housing, a balancing bar under the arm pivotally mounted with a portion projecting forwardly from the housing and a rear portion extending into the housing, a member for cushioning tilting movement of the balancing bar and arm during opening and closing of the closure, a weight under the forward portion of the balancing bar, a cross bar extending transversely of the rear portion of the balancing bar, means for supporting the weight and the cross bar and shifting the same longitudinally of the balancing bar towards and away from each other, a cam between the arm and the cross bar for imparting tilting movement to the arm and imparting opening and closing movement to the closure when the balancing bar is tilted, and a second arm extending forwardly from the deflector plate and engaging the cross bar for imparting tilting movements to the deflector when the balancing bar is moved.
